UNITED STATES PATENT OFFICE.

RUFUS K. CHANDLER, OF RICHMOND, VIRGINIA.

WRISTBAND OF SHIRTS.

Specification of Letters Patent No. 12,899, dated May 22, 1855.

To all whom it may concern:

Be it known that I, RUFUS K. CHANDLER, of Richmond, in the county of Henrico and State of Virginia, have invented a new and 5 Improved Mode of Making the Wristbands of Shirts and other Similar Garments; and I do hereby declare that the following is a full and exact description thereof, reference being had to the accompanying drawings, 10 making a part of this specification.

The nature of my invention consists in making a wristband of two corresponding flaps *a*, *b*, combined with each other and with the portion *d*, of the wristband that is 15 secured to the shirt, in such a manner that both flaps can be turned forward, as represented in Figures 1, and 2; or the outer flap *a*, be turned backward, so as to expose the under flap *b*, as represented in Figs. 3 20 and 4; or the under flap *b* may be turned under, as represented in Fig. 5. The flaps *a*, *b*, and the portion *d*, of the wristband, may be stitched or otherwise, to suit the taste of the maker or wearer. Usually both 25 flaps *a*, and *b*, and the upper portion *d*, of the wristband, are so stitched as to make a handsome finish upon their outer sides. The flaps should be ironed separately, so as to present smooth outer surfaces. In wearing

the shirt supplied with my improved wristbands, both flaps should be turned forward at first, and worn until the outer flaps are soiled, and then they should be turned back into the position shown in Figs. 3, and 4, for the purpose of exposing the clean outer surfaces of the under flaps *b*, *b*. Or the outer flaps, may be at first turned backward, and the shirt worn until the under flaps are soiled, and then the said under flaps be turned under and the outer flaps turned forward. As the wristbands of a shirt are always the first exposed portion of it to get soiled, my improved wristbands enable a shirt to be decently worn nearly twice as long as a shirt supplied with the usual form 45 of wristbands.

What I claim as my invention and desire to secure by Letters Patent, is—

Making wristbands with double flaps, substantially in the manner and for the purpose 50 herein set forth.

The above specification of my improvement in shirt sleeve wristbands, signed and witnessed this 11th day of April 1855.

RUFUS K. CHANDLER.
